CENTER MOUNTED WINDOW OPERATOR

Andrew J. Campbell, Southfield, and Robert L. Fischer,
Detroit, Mich., assignors to Al-Craft Manufacturing
Company, Troy, Mich., a corporation of Michigan

Filed June 15, 1965, Ser. No. 85,736

Term of patent 14 years

(Cl. D10—10)

FIG. 1

FIG. 2

FIG. 3

FIG. 4

FIG. 5

FIGURE 1 is a side elevational view of the center mounted window operator showing our new design, being partially broken away and indicating the mounting of the operator to a frame member;

FIGURE 2 is a top plan view, partially broken away, of the operator;

FIGURE 3 is a view in end elevation of the operator, also indicating its mount to a frame member;

FIGURE 4 is a further end elevational view, but from the opposite end of the operator; and

FIGURE 5 is a bottom plan view, partially broken away, of the operator.

The dominant features of the design reside in the portions shown in full lines, the broken away showing of the window sill being for illustrative purposes only.

The handle is omitted in FIGS. 2 to 5 for ease of illustration.

We claim:

The ornamental design for a center mounted window operator, substantially as shown and described.
